Primary Examiner — Jeffrey D Asch(74) *Attorney, Agent, or Firm* — Staas & Halsey LLP(57) **CLAIM**

The ornamental design for a mobile information terminal, as shown and described.

DESCRIPTION

FIG. 1 is a perspective view of front, bottom and left side of a mobile information terminal showing our new design;
FIG. 2 is a perspective view of rear, bottom and left side thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged view of A-B portion in FIG. 5;

FIG. 10 is an enlarged view of A-C portion in FIG. 5; and,
FIG. 11 is a sectional view taken along line 11-11 in FIG. 3 with an internal mechanism omitted.

The portions of the article in broken lines are shown for illustrative purposes only and form no part of the claimed design.

1 Claim, 6 Drawing Sheets(56)
